DESIGN FOR A KNITTED SWEATER

Morris Philip, New York, N. Y.

Application May 9, 1941, Serial No. 109,870

Term of patent 3½ years

To all whom it may concern:

Be it known that I, Morris Philip, a citizen of the United States and a resident of the city of New York, in the county of Bronx and State of New York, have invented a new, original, and ornamental Design for a Knitted Sweater, of which the following is a specification, reference being had to the accompanying drawing, forming a part thereof.

Fig. 1 is a front view of a knitted sweater showing my design.

Fig. 2 is a rear view thereof.

The characteristic feature of my design resides in a sweater having the specific contrastingly colored emblem knitted thereinto and lying on the same plane.

I claim:

The ornamental design for a knitted sweater, substantially as shown and described.

MORRIS PHILIP.
